[57] CLAIM

The ornamental design for a portable golf seat, as shown and
described.

DESCRIPTION

FIG. 1 is a front perspective view of a portable golf seat
showing my ornamental design;

FIG. 2 is a top plan view thereof;

FIG. 3 is a right side elevational view thereof;

FIG. 4 is a bottom plan view thereof;

FIG. 5 is a front elevational view thereof;

FIG. 6 is a left side elevational view thereof;

FIG. 7 is a rear elevational view thereof; and,

FIG. 8 is a top plan view thereof with a top flap drawn to
expose a portion of an inner pocket of the portable golf seat.
